UNITED STATES PATENT OFFICE.

FRITZ DÜHRKOP, OF NEW YORK, N. Y.

BAKER'S OVEN.

SPECIFICATION forming part of Letters Patent No. 380,556, dated April 3, 1888.

Application filed October 21, 1887. Serial No. 252,985. (No model.)

To all whom it may concern:

Be it known that I, FRITZ DÜHRKOP, of New York, county and State of New York, have invented a new and Improved Baker's ⁵ Oven, of which the following is a specification.

This invention relates to a baker's oven of novel construction; and it consists in the various features of improvement more fully pointed out in the claims.

10 In the accompanying drawings, Figure 1 is a vertical transverse section of my oven on the lines $x x' x'$, Figs. 2 and 4. Fig. 2 is a horizontal section on line $y y$, Fig. 1. Fig. 3 is a similar section on the line $z z$, Fig. 1; and Fig. 15 4 is a similar section on the line $w w$, Fig. 1.

The letter a represents the fire-place of the oven, divided from flues b at the right and left by means of the partition c . The fire-place a and the flues b are provided with arched 20 roofs d , as shown. These roofs separate the fire-place and the flues from a large air-space, e , situated directly beneath the entire base or floor f of the baking-chamber g , such floor being supported by an offset on the side walls, h , 25 of the oven. The baking-chamber g is provided with a double arched roof, $i i'$, between which the partitions j form a series of flues, k k' . The heat and products of combustion travel to the rear of the fire-chamber a , thence 30 around the partitions c to the flues b . After having traversed the flues b the heat passes upward through vertical flues l and into the two outward flues, k' , thence around partitions j to central flues, k , and finally out of stack m .

Thus the oven is properly and uniformly 35 heated at the top and bottom. The air-space e between the roofs d and the base f of the oven I deem of considerable importance. The heat which is radiated upward from the fire-chamber a and flues b heats the air in the space ⁴⁰ e . This heated air imparts to the baking-chamber g a uniform degree of heat, which greatly facilitates and improves the baking operation.

n are dampers in partitions c for throwing the heat directly from the fire-chamber a into 45 the flues b .

What I claim is—

1. The combination of roofed fire-chamber a and flues b with baking-chamber g , and with an intervening air-space, e , substantially as 50 specified.

2. The combination of fire-chamber a and flues b , with which said fire-chamber communicates, with the oven g , and with an intervening air-space, e , and with a double roof, $i i'$, 55 and flues l , connecting the flues b with the space between said double roof, substantially as specified.

3. The combination of fire-chamber a and flues b with the superposed air-space e , super- 60 posed baking-chamber g , having double roof $i i'$ and flues $k k'$, and with the upright flues l , connecting flues b with flues k' , substantially as specified.

F. DÜHRKOP.
